AUTOMOBILE FLOOR MAT

William C. Gerber, Wooster, Ohio, assignor to Rubber-maid Incorporated, Wooster, Ohio, a corporation of Ohio

Filed May 12, 1969, Ser. No. 17,110

Term of patent 14 years

Int. Cl. D12—14

U.S. Cl. D14—5

FIG. 1

FIG. 2

FIG. 3

FIG. 4

FIG. 5

FIG. 1 is a plan view of an automobile floor mat and the like embodying my new design.

FIG. 2 is a side elevational view thereof.

FIG. 3 is a fragmentary sectional view on line 3—3 of FIG. 1.

FIG. 4 is a fragmentary sectional view on line 4—4 of FIG. 1.

FIG. 5 is a fragmentary sectional view on line 5—5 of FIG. 1.

I claim:

The ornamental design for an automobile floor mat, as shown.
